UNITED STATES PATENT OFFICE.

ROBERT L. McINTOSH, OF INDIANA HARBOR, INDIANA, ASSIGNOR TO INLAND STEEL COMPANY, OF CHICAGO, ILLINOIS, A CORPORATION OF DELAWARE.

HEATER FOR ROLLS.

Application filed December 3, 1924. Serial No. 753,680.

The present invention relates to heaters for rolls.

More particularly the present invention relates to means for heating rolls such as are used in sheet mills. Various means have been devised and are being used for accomplishing such heating. The present invention relates to electrical heating means and has for one of its objects the provision of electrical heating means which will have improved efficiency and economy in operation.

A further object is to provide electrical heating means in which the magnetizing effect of the heating means upon the rolls will be a minimum.

A further object is to provide an electrical heating structure for heating rolls in which the magnetizing effect will be a minimum and which will involve a minimum of expense for repairs.

A further object is to provide heating means for rolls which will minimize the magnetizing effect of the electrical heating current upon the rolls while retaining the advantage that said heating coils may be placed in close proximity to the heating rolls.

A further object is to provide an improved method of applying the heating current, whereby the magnetizing effects of said current will be minimized.

Further objects will appear as the description proceeds.

Referring to the drawings—

Figure 1 is a view in elevation of a roll heating structure, the rolls to be heated being shown in transverse section;

Figure 2 is a view on an enlarged scale of a portion of the structure shown in Figure 1;

Figure 3 is a fragmentary view illustrating the heating structure applied to rolls to be heated, said view being taken in side elevation;

Figure 4 is a detail view, parts being broken away, showing one of the heating elements;

Figure 5 is a sectional view taken along the plane indicated by the arrows 5—5 of Figure 4;

Figure 6 is a diagrammatic view illustrating the electrical connections of the heating elements; and

Figure 7 is a view illustrating the relative spacing of electrical resistor wire with

reference to the folds thereof and the roll to be heated.

Referring particularly to Figure 1, the upper roll 11 and the lower roll 12 are shown supported in a common type of roll stand 13. This roll stand forms no part of the present invention and need not be described in detail. The roll heater comprises two separate heating members A and B, one of which is applied to each side of the pair of rollers. These heating members are similar to one another and the description of one will be sufficient for the description of both. The heating members A and B comprise a frame 14 of angle members, from which the handles 15—15 extend at the upper ends. Said heating members are provided at their lower ends with outstanding portions provided with the rollers 16—16, by means of which said members may be trundled about from place to place. The heating members A and B are clamped together, according to the illustrated embodiment, by means of the bolts 17 and 18 at their upper and lower ends, respectively.

Flexible jacket members 19 are secured to the upper portions of the frame and similar jacket members 20 are secured to the lower portion of the frame, said frames having circumferential curvatures whereby said jackets 19—19 and 20—20 may conform to the peripheries of the rolls 11 and 12. It will be noted that the jackets 19 and 20 are secured to the frames 14—14 only at their extremities, the intermediate portions of said jackets remaining flexible and free to be drawn into contact with the rolls. Adjusting bolts 21—21 are threaded through certain relatively fixed frame members 22—22 and are provided with the enlarged ends 23—23 engaging the outturned edges 24 and 25 of the jackets 19 and 20.

As shown in detail in Figure 2, the jacket 19 is provided with a lining 26 of asbestos or similar heat insulating material. A plurality of heating elements 27—27 are secured upon the inner face of the insulating material 26 and are provided with the connector lugs 27'. As will be explained hereinafter, the several heating elements 27—27 are connected in parallel circuits to the electric supply mains, whereby each of said elements carries a fractional part of the total heating current.

Referring now particularly to Figures 4 and 5, it will be noted that the heating ele-

ments 27 are made in the form of strips. Said strips are mounted in parallel relation with the rolls to be heated and include a casing of magnetic material such as soft iron. Said casing, which is indicated by the numeral 28, comprises the channel-shaped member 29 having the inturned edges 30—30. Said casing also includes the strip 31 of magnetic material mounted within the in-turned edges 30—30. Said casing 28 houses the resistor wire 32, which according to the present invention is non-inductively shaped, that is to say—said resistor wire is folded upon itself in the manner shown in Figure 4, whereby the magnetizing effect of any fold 33 of said resistor wire is balanced by the magnetizing effect of the neighboring fold 33 of resistor wire. Said folds 33—33 should be located close to one another, the space between adjacent folds being less than the space between the resistor wire 32 and the roll to be heated. This spacing is illustrated in Figure 7. By reason of this arrangement of the resistor wire, stray magnetic effects upon the rolls to be heated are minimized. Not only does the non-magnetizing folding of the resistor wire with its closely spaced folds minimize the effect of stray magnetic fluxes, but a further protection of the rolls against magnetism is accomplished by reason of the jacket of magnetic material housing the resistor wire 32. It will be understood that the resistor wire may be embedded in cement 34 or other suitable material within the casing 28.

Figure 6 illustrates the electrical connections of the heating elements 27—27. The numerals 35 and 36 indicate two supply conductors of an electric circuit. As clearly shown in Figure 6, the two terminals of each of the heating elements 27—27 are connected

to the electrical supply conductors 35 and 36, whereby each of the heating elements 27—27 carries only a fractional part of the total heating current, thereby reducing the intensity of their magnetic effect. A further advantage of this construction is that in the event of failure of any of the heating elements the remainder of said elements will still be operative, whereby the failure of a single element or a few elements will not put the total heater out of operation.

By reason of the present invention the efficient heating of the rolls is accomplished. It will be clear that the jackets 19—19 and 20—20 containing the heating elements 27—27 may be drawn tightly against the rolls 11 and 12 or may loosely embrace said rolls, as preferred. The magnetizing effects upon the rolls will be reduced to a minimum and the danger of shut downs due to failure of any of the elements will be minimized.

Though a preferred embodiment of the present invention has been described in detail, it will be clear that many modifications will occur to those skilled in the art. It is intended to cover all such modifications that fall within the scope of the appended claim.

What is claimed is:

A heater for rolls, comprising a plurality of heating elements, means for holding said elements adjacent to the periphery of the roll to be heated, each of said elements including a resistor wire, said wire being folded upon itself in a non-magnetizing manner, the folds of said wire being relatively close together with respect to the distance to the roll.

Signed at Indiana Harbor, Indiana, this 28th day of Nov., 1924.

ROBERT L. McINTOSH.
